UNITED STATES PATENT OFFICE.

FAIRLEIGH S. DICKINSON, OF RUTHERFORD, NEW JERSEY.

SYRINGE.

1,130,493.

Specification of Letters Patent.

Patented Mar. 2, 1915.

Application filed October 27, 1914. Serial No. 868,812.

To all whom it may concern:

Be it known that I, FAIRLEIGH S. DICKINSON, a citizen of the United States, and a resident of Rutherford, in the county of Bergen and State of New Jersey, have invented new and useful Improvements in Syringes, of which the following is a full, clear, and exact description.

The object of the invention is to provide certain new and useful improvements in 10 syringes and like devices whereby the plunger is held against accidental dropping out of the barrel.

In order to accomplish the desired result, 15 use is made of a combined finger piece and plunger retainer, of which the finger piece is held on the barrel and the plunger retainer is in the form of a coil spring attached at its ends to the finger piece and 20 engaging the outer surface of the plunger so as to hold the latter against accidental dropping out of the barrel.

A practical embodiment of the invention is represented in the accompanying drawings forming a part of this specification, in 25 which similar characters of reference indicate corresponding parts in all the views.

Figure 1 is a side elevation of an ordinary syringe provided with the combined finger piece and retaining device; Fig. 2 is a cross section of the same on the line 2—2 of Fig. 1; and Fig. 3 is a perspective view of the combined finger piece and retaining device.

In syringes, especially those made of 30 glass, as now generally constructed, the plunger is liable to drop out of the barrel when pointing the nozzle thereof in an upward direction, and hence the plunger is liable to be broken, injured or soiled, so as 35 to render the syringe unfit for use. In order to prevent the plunger from accidentally dropping out of the barrel, use is made of a retaining device presently to be described 40 in detail.

The syringe shown in Figs. 1 and 2 consists of the usual barrel A in which reciprocates a piston B provided at its outer end with a suitable handle B'. The barrel A is provided at its outer end with the usual discharge nozzle A' and at the rear end with a flange A² against which rests a ring C encircling the barrel A and provided with outwardly extending finger pieces D adapted to be taken hold of by the user of the syringe 50 when actuating the plunger B in the barrel A for ejecting the liquid contained in the

barrel. On the finger pieces D are held loops E to which are secured the ends of a coil spring F which normally extends diametrically across the ring C but is adapted 60 to be deflected sidewise when inserting the plunger B into the barrel A so that the spring F is placed under tension and bears against the outer surface of the plunger B with sufficient force to hold the plunger 65 against accidental movement or dropping out of the barrel A when holding the syringe with the nozzle A' pointing upward, as indicated in Fig. 1. It is understood that the spring F does not interfere with the operator 70 reciprocating the plunger B in the barrel A for drawing in the liquid or ejecting the same in the usual manner, but the spring F on account of being under tension and encircling a portion of the plunger B holds the 75 latter against accidental movement as previously explained.

The finger piece and retaining device shown and described is very simple in construction and can be readily placed in position on the syringe for the purpose mentioned.

When using the syringe for ejecting a fluid contained in the barrel A, the operator 80 engages the finger pieces D with the forefinger and the middle finger, and with the thumb presses the plunger B inward to eject the fluid through the nozzle A'.

Having thus described my invention, I 85 claim as new and desire to secure by Letters Patent:

1. A syringe attachment, comprising a coil spring adapted to bear on the plunger adjacent the rear end of the barrel to hold the plunger against accidental movement 90 in the barrel, and a support adapted to engage the rear end of the barrel and to which the ends of the suspended coil spring are attached.

2. A syringe attachment, comprising a ring adapted to engage the barrel of the syringe at the rear end thereof, finger pieces on the said ring, and a coil spring connected at its ends to the said finger pieces and normally extending diametrically across the 95 said ring, the said coil spring being adapted to be placed under tension by the syringe plunger to bear on the latter.

3. A syringe attachment, comprising a ring adapted to engage the barrel of the syringe at the rear end thereof, finger pieces on the said ring, loops held on the said 100

finger pieces and bearing against the said ring, and a coil spring attached at its ends to the said loops to normally extend diametrically across the ring, the said spring being 5 adapted to be deflected and placed under tension by the syringe plunger to bear on the surface thereof.

In testimony whereof I have signed my name to this specification in the presence of two subscribing witnesses.

FAIRLEIGH S. DICKINSON.
